UNITED STATES PATENT OFFICE.

HERBERT W. SMITH, OF SOMERVILLE, MASSACHUSETTS, ASSIGNOR OF ONE-HALF TO WALTER H. POPE, OF BOSTON, MASSACHUSETTS.

DESIGN FOR A TROLLEY-POLE.

SPECIFICATION forming part of Design No. 30,548, dated April 11, 1899.

Application filed March 2, 1899. Serial No. 707,532. Term of patent 7 years.

To all whom it may concern:

Be it known that I, HERBERT W. SMITH, of Somerville, in the county of Middlesex and State of Massachusetts, have invented and produced a certain new and original Design for Trolley-Poles, of which the following is a specification, reference being had to the accompanying drawings, forming a part thereof.

Figure 1 represents a perspective view of a trolley-pole embodying my design. Fig. 2 represents an end view showing the larger end of the pole.

The leading feature of my design consists in the slender tapering pole having a short external smooth upper end and corrugations extending therefrom longitudinally of the pole to the lower end, said corrugations presenting a series of alternate ridges and depressions on the surface of the pole.

a represents a trolley-pole embodying my design, the same being tubular and slender and tapering gradually from one end to the other.

a' represents the ridges, and *a²* the dépressions, which extend lengthwise of the pole and decrease in amplitude from the larger nearly to the smaller end.

a³ represents the short smooth upper end of the pole.

I claim—

The design for a trolley-pole, substantially as described and shown.

In testimony whereof I have affixed my signature in presence of two witnesses.

HERBERT W. SMITH.

Witnesses:

C. F. BROWN,
A. D. HARRISON.
